PROTECTIVE NET ATTACHMENT FOR CRIB BEDS

Norman C. Le Roy, Miami, Fla.

Application May 12, 1950, Serial No. 161,618

3 Claims. (Cl. 5—100)

1

This invention relates to attachments for crib beds and is an improvement over the device shown in my co-pending application for similar devices, filed April 1, 1950, Serial No. 153,462.

The invention relates primarily to a shiftable net device that is mounted upon the side of the crib to generally be positioned to catch bottles, toys or the like that might be thrown from the crib by the occupant, or shoved between the usual slatted sides, the articles rolling downwardly in the net to its lowermost point where they may be subsequently retrieved.

The invention contemplates novel means for supporting a net device upon either or both sides of a crib bed, whereby the net is disposed at an angle outwardly with its lower portion arranged in close parallelism with the lower edge of the crib side to thereby extend the area of protection outwardly of the crib to a point calculated as being well beyond the range possible for an infant to throw articles such as nursing bottles, toys or the like.

An important object of the invention resides in the means for detachably mounting the net upon the crib, requiring no screws or other fastening devices that would damage or mar the finish of the bed, with the lower portion of the net supported in fixed relation to the mattress and springs of the bed in such manner that the side of the crib may be lowered, carrying with it the net supporting frame, yet maintaining the lower edge of the net in its fixed position.

The invention further contemplates a safety protection net for crib beds that will normally move to an angular position with respect to the side of the crib and will maintain such angularity without the aid of springs, set screws or the like, yet will readily shift inwardly to lie in parallel engagement with the side of the crib when engaged by the body of an attendant, to thereby offer no objectionable projections that would interfere with the access to the occupant of the crib.

Another object of the invention resides in the extreme simplicity of the structure and the ease with which it can be assembled and attached to the crib, has relatively few parts that are of such nature that readily permit the complete collapsing of the device for storage and shipment in a relatively small container or carton, is strong, durable, employs a net having relatively wide mesh that offers no resistance to the passage of air therethrough, is cheap to manufacture and is highly efficient in use.

Other objects and advantages of the invention

will be readily apparent during the course of the following description, reference being had to the accompanying drawings wherein has been illustrated structures embodying the invention and wherein like characters of reference are employed to denote like parts throughout.

In the drawings:

Figure 1 is a perspective view of the assembled device prior to mounting upon the side of the crib bed.

Figure 2 is a transverse vertical section through the device as mounted to the side of the crib.

Figure 3 is a fragmentary front elevation of one end of the device in mounted position and with the net removed.

Figure 4 is a fragmentary perspective of the supporting and positioning means for the lower edge of the net.

Figure 5 is a perspective view of a modified form of mounting support for the net frame and,

Figure 6 is a side elevation of the structure of Figure 5.

Referring specifically to the drawings and particularly to Figures 1 to 4 inclusive, the numeral 5 designates a crib bed of any well known construction having ends 6, sides 7, a mattress supporting spring 8 and a mattress 9. The sides 7 are customarily movable in a vertical plane for convenient access to an occupant of the crib. The sides 7 include top and bottom rails, connected by spaced slats. The rails are vertically shiftable upon track rods 10. The spring and its supported mattress may be adjustable vertically, as is customary in some types of such beds. It is pointed out however, that the device of the present invention is adjustable as to length and height to readily adapt its structure and mounting means to crib sides of varying dimensions.

The preferred means for rigidly mounting the net and its associated parts to a crib side 7, consists of an elongated tubular member 11, having interior right and left hand screw threads for the major portion of its length from either end. Threaded rods 12 and 13 engage the threads of the tube 11 and project above and below the tubes 11 at each end of the crib side 7. The rods 12 carry adjustable U-shaped saddles 14, one portion of the saddles being fixed upon the rods 12, while the other portion is shiftable laterally to accommodate rails of different thicknesses. The rods 13 terminate in enlarged cylindrical bosses 15, slotted at 16 for the pivotal reception of reduced ends of tubular L-shaped frame sockets 17, pivotally supported by pins 18.

The sockets are limited in their outwardly swinging movement by the abutment of the reduced end at one end of the slots 16, yet may swing inwardly to lie substantially parallel with the tubes 11, for a purpose to be described. The bosses 15 at their outer ends are welded or otherwise attached to adjustable saddles 19, one portion of the saddles being fixed to the bosses, while the other portion is shiftable laterally to accommodate it to rails of different thicknesses.

In mounting the supports, including the tubes 11, saddles 14 and 19 and sockets 17, the tubes are held in the hand and the rods 12 and 13 are screwed inwardly to a position where the saddles clear the inner edges of the top and bottom rails of the side 7. The operator then engages the lower saddles 19 over the lower rail, at points adjacent the ends and the saddles 19 shifted inwardly to snugly engage the sides of the rails. The upper saddles having been adjusted to the width of the upper rail, the tubes 11 are rotated, causing the rods 12 and 13 to be extended outwardly until the upper saddles firmly engage the upper rail. The support thus acts like a turn-buckle and rigidly positions the device within the side 7 against shifting accidentally without the use of screws or other fastening devices, such as has been disclosed in my co-pending application above identified. The mounting is thus adaptable to cribs having sides of varying height and is interchangeable from one crib to another without in any way marring the finish thereof. If found desirable, the saddles may be lined with rubber or felt as an additional safeguard against marring the finish. It is contemplated that the tubes 11 shall be formed of aluminum, in which case the rods 12 and 13 will be formed of steel in order to prevent corrosion of the threads, such as would occur, if both the tubes and the rods were formed of aluminum. However, the particular material employed forms no part of the present invention. While it is contemplated that the saddles shall be formed of metal, either cast or stamped, it follows, that they may be formed of plastic, rubber or any other desirable material.

Means are employed to support a net 20, comprising parallel end rods 21, detachably supported within the sockets 17. The rods 21 are of identical length and are connected at their upper ends by a horizontal rod 22, through the medium of tubular L-shaped couplings 23. The rod 22 is longitudinally extensible and is formed in two parts, connected in axial alignment by a tubular sleeve 24. The net 20 includes end panels 25 and a side panel 26. The end panels 25 are provided with hems 27 at their ends for engagement over the support tubes 11, while the side panel 26 is provided with upper and lower hems 28 and 29, the upper hem 28 receiving the rod 22, while the lower hem 29 receives a rod 30. The rod 30 is formed in two sections, connected by a tubular sleeve 31, whereby the rod may be extended in length to adapt it to crib sides of varying lengths. The sections of the rod 30 at their outer ends, are provided with axial openings 32 for the detachable reception of the ends 33 of brackets, designated as a whole by the numeral 34. The brackets are employed to properly position the rod 30 and the lower edge of the net 20 with respect to the bed springs and mattress and for maintaining the lower edge of the net against or closely adjacent the side of the crib to prevent articles passing therebetween. The brackets 34

includes the rod engaging end 33, extending from a coil 35. The opposite end of the coil extends outwardly at a right angle to the end 33, is then bent downwardly at a right angle and then bent forwardly to provide a relatively long extension 36. In use, the coil 35 is positioned over the tubes 11, as clearly shown in Figure 1, with the extensions 36 extending forwardly to be subsequently positioned under the mattress 9 to lie upon the springs when the structure is mounted upon the side 7 of the crib.

In the use of the invention so far described, the several parts being in disassembled relation, the operator first removes the threaded rods 12. The bracket coils are then dropped over the tubes 11 and the hems 27 likewise positioned over the tubes 11. The rods 12 are then replaced. The rods 22 and 30 are engaged in their respective hems 28 and 29 and the end rods 21 are connected with the rod 22 through the medium of the couplings 23 and their lower ends engaged in the sockets 17. The ends 33 of the brackets 34 are then engaged in the openings 32 and the device is then ready for mounting upon the side 7 of the crib. The supports, including the tubes 11 are then adjusted and rigidly clamped within the side 7 as before pointed out. In this position, the extended ends 36 of the brackets overlie the springs 8 of the bed. The mattress 9 prevents vertical shifting of the brackets 34 and maintains the same relative position of the mattress and the lower edge of the net, regardless of the vertical position of the side 7. When the operator desires to administer to the occupant of the crib, he merely moves against the rod 22, which action causes the entire frame consisting of the rods 21 and 22 to shift inwardly in an arc, determined by the pivotally mounted socket 17, to lie against the side of the crib in substantially parallel engagement, thus offering no interference to the proper attention of the occupant. As the operator moves away from the crib, the frame automatically swings outwardly to again position the net in its angular relation to the side 7. Articles falling between the slats of the side 7 or articles thrown over the top 7 will roll or slide downwardly to the lower part of the net to lie against the side of the crib and the bottom of the net as determined by the rod 30, where they can be conveniently retrieved. The device can be quickly removed and disassembled and the net removed for washing, when desired. The bottom edge of the net is always maintained in engagement with the side of the crib through the medium of the extensions 36 and when the crib side 7 is raised or lowered, the coils 35 and hems 27 merely slide with respect to the tubes 11. This permits freedom of movement of the sides 7 at all times with no interference from the net structure. The vertical bending of the bracket 34 is to permit adequate clearance of the bracket with respect to the lower rail of the side when the bed springs are moved to their maximum lower position. The springs, as illustrated in Figure 2 are somewhat elevated above the lower rail of the side.

Referring now to Figures 5 and 6, a modified form of mounting has been illustrated for the shiftable support of the frame of the net. In this form of the invention, tension clamps 37 are adapted to engage over the lower side of the lower rails, while tension clamps 38 are adapted to engage over the upper edges of the upper rails. The clamps are U-shaped and include a long tongue 39, and a relatively short tongue 40, con-

nected by a horizontal strip 41. The tongues 40 are inclined inwardly and are flexible and provide a means to adapt the clamps to rails of varying width. The clamps in use are merely sprung over the rails. The long tongues are provided with bayonet shaped slots 42 and the material surrounding the slots is pressed outwardly to provide a socket for the reception of offset coiled ends of elongated, close packed coil springs 43. The clamps and the springs serve as the mounting means for the net frame and may be substituted for the tubes 11 and saddles 14 and 19. The lower clamp 37 is provided with a forwardly extending U-shaped bracket 44, the forward end of which is inclined. The bracket 44 pivotally supports the lower end of an end rod 45, of the net frame, through the medium of a pivot pin 46. The angularity of the end of the bracket determines the angularity of the net. In all other respects, the net construction, frame and operation is identical to that already described. The clamps 37 and 38 may be formed of any desirable material, such as metal, plastic, rubber or the like.

In the use of this form of the invention, the operator engages one end of the spring 43 with the lower clamp 37 and the clamp is engaged with the lower rail of the side. The clamp 38 is then engaged over the upper rail and the opposite end of the spring 43 is connected thereto through the medium of the bayonet slot 42. Obviously, before the spring 43 is connected to the upper clamp, the brackets 34 and hem 21 are positioned thereover. The springs 43 will be properly plated to provide a smooth surface over which the hem 21 and coil 35 will easily slide when the side 7 is lowered and raised.

From the foregoing, it will be observed that a very simple and novel construction has been provided for the mounting of a safety net attachment for crib beds. The device readily adapts itself to various sizes of beds and can be produced in various materials. The present structure for the support of the net is preferably wood and aluminum, although it is contemplated that the entire net frame shall be formed of metal tubing or other desirable material. The use of the device will result in a considerable saving from the standpoint of cost of broken bottles or the like, where the net is not employed.

It is to be understood, that the invention is not limited to the precise construction and arrangement, but that changes in the shape, size, arrangement of parts and substitution of materials may be resorted to as fall within the spirit of the invention or the scope of the subjoined claims.

Having described my invention, what I claim as new and desire to secure by Letters Patent is:

1. A safety net attachment for a crib which has a drop side provided with openings therein, said safety net comprising a net, a plurality of mounting means adapted to be mounted on the lower part of said drop side, a plurality of supports, each of which is secured at one end to one

of said mounting means, each of said supports being vertically adjustable with respect to the mounting means, each of said supports having an adjustable extension at the other end thereof, each of said extensions adapted to be connected to the upper part of said drop side, a U-shaped frame pivotally connected to at least two of said mounting means, the net of said safety net being secured at one end to one of said supports and at the other end to another of said supports, said net also being secured intermediate its ends to said U-shaped frame, a rod carried by the lower part of said net, brackets connected with the opposite ends of said rod and with the supports, the brackets being extended to underlie a mattress supported in the crib whereby the lower part of said net may be brought into releasable engagement with the lower part of the drop side.

2. The device as in claim 1, wherein the mounting means comprise inverted U-shaped saddles that engage over the lower part of the drop side, each of said saddles provided with an upstanding cylindrical boss that is apertured for the pivotal reception of the U-shaped frame, each of said cylindrical bosses having axial reduced cylindrical extensions that are screw-threaded, each of said supports being tubular and internally threaded in opposite directions from each end, the supports at their lower ends having adjustable threaded engagement with the threads of the axial extensions, the upper end of each support having threaded engagement with threaded extension rods, each of said threaded extension rods being connected with a U-shaped saddle that engages an upper part of the said drop side.

3. The device as in claim 1, wherein the rod carried by the lower part of said net is provided at its opposite ends with means to each receive an end of bracket devices, one bracket device being fixed at one end of the rod and another bracket device being fixed to the opposite end of the rod, each of the brackets being bent intermediate their lengths to form a coil, the coil of one bracket embracing one of said supports, the coil of the other bracket embracing another of said supports, each of the brackets provided with an extension that underlies a mattress supported in the crib, the brackets and the rod serving to support the lower part of the net in releasable engagement with the lower part of the drop side.
